DESIGN FOR AN INSIGNIA

Abner A. Ruben, New York, N. Y.

Application November 18, 1933, Serial No. 49,797

Term of patent 7 years

To all whom it may concern:

Be it known that I, ABNER A. RUBEN, a citizen of the United States, residing at New York, in the county of New York and State of New York, have invented a certain new, original, and ornamental Design for Insignia, of which the following is a specification.

The design consists of an emblem or insignia, as illustrated in the accompanying drawing, which is made a part hereof. The emblem is substantially thin and flat.

I claim:

The ornamental design for an insignia as shown and described.

In witness whereof, I have hereunto set my hand at New York, New York, this 3rd day of November, A. D. nineteen hundred and thirty-three.

ABNER A. RUBEN.
